UNITED STATES PATENT OFFICE.

HENRY SCHEELE, OF MILWAUKEE, WISCONSIN.

TURBINE-ENGINE.

No. 808,950.

Specification of Letters Patent.

Patented Jan. 2, 1908.

Application filed July 12, 1905. Serial No. 269,817.

To all whom it may concern:

Be it known that I, HENRY SCHEELE, residing in Milwaukee, in the county of Milwaukee and State of Wisconsin, have invented new and useful Improvements in Turbine-Engines, of which the following is a description, reference being had to the accompanying drawings, which are a part of this specification.

10 This invention relates to turbine-engines, and comprises a turbine-engine for use with steam or other pressure fluid which will be balanced in the pressure upon its rotating parts, so as to cause no undue end thrust.

15 This invention also comprises a turbine-engine having a plurality of concentric series or rings of blades or buckets adapted to successively receive the steam or other pressure fluid and be influenced thereby to produce 20 the same tendency upon the rotating member, the transfer of pressure fluid from one set of turbine-blades to another being accomplished by means of suitable nozzles.

25 This invention also comprises a turbine-engine having blades of novel construction and mounted in a new manner.

With the above and other objects in view the invention further consists in the novel details of construction and arrangement of parts 30 as herein set forth and their equivalents.

35 Referring to the accompanying drawings, in which like characters of reference indicate the same parts in the several views, Figure 1 is a side elevation, partly in vertical central section, of a turbine-engine constructed in accordance with this invention. Fig. 2 is an 40 end elevation of the stationary portion thereof with the inlet-chamber partly sectioned and the nozzle-passages shown in dotted lines. Fig. 3 is a plan view of a portion thereof. Fig. 4 is a sectional view of one of the nozzles. Fig. 5 is a detail view showing 45 several turbine-blades in their relation to each other, and Fig. 6 is a plan view of one of the turbine-blades.

In the drawings, 10 represents a central stationary body portion of the turbine which is provided with any suitable supporting-base 11 and which has shell-like outer casings 12 removably secured to its opposite sides. The casings 12 form suitable bearings (not shown) for the rotatable part of the turbine, which comprises a pair of movable members 13 on opposite sides of the stationary member 10 and connected together through a central opening of said stationary

member by means of a boss 14 on one movable member threading into a sleeve 15 on the other movable member. Each of the movable members 13 has a shaft 16, which is journaled in the outer casings 12, as before mentioned, and which is provided with a suitable steam-tight packing 17 of usual construction to prevent the discharge of steam which may accidentally find its way beyond the movable members. As the two sides of the stationary member 10 and the two movable members 13, which actively coöperate therewith, are identical in their construction, respectively, the description will be confined to the construction of one side of said stationary member and the movable member adjacent thereto.

The side of the stationary member 10 and the inner face of the movable member 13 are fitted to each other very closely, and at the outer edges of their meeting faces they are provided with steam-tight connections, comprising concentric flanges 18 on the former fitting within concentric grooves 19 in the latter. The active face of the movable member 13 is also cut away or recessed between this steam-tight connection and its hub or connection with the other movable member to receive a number of concentric series 25 of blades 20. Each blade has an oblong rectangular base 21, with the integral outwardly-bent blade portion shorter than the base and extending at an angle thereto. The blades of the outer set have their bases 21 30 fitted into an annular groove around the outer edge of the cut-away portion of the movable member 13 and are arranged one after another in the manner shown in Fig. 5, their upstanding inclined blade portions standing 35 flush with the inner face of said movable member and against the outer edge of the cut-away portion. The circular series of blades thus arranged is firmly secured to the movable member 13 by means of a clamping strip or ring 22, which is countersunk within the member and has a shoulder on each side to receive the projecting ends of the bases of the blades, said ring standing flush with the outer edges of the blades and against their 40 end edges and being secured to the member 13 by means of screws 23. Any number of other concentric series of blades may be attached in the same manner, there being three in all, as here shown, the last series fitting 45 within a groove at the inner edge of the cut-away portion of member 13, corresponding

to the groove in which the first or outer series of blades was inserted, and the last two sets of blades being clamped by the inner clamping-ring 22. In this manner the inner face of the movable member 13 is provided with three concentric rings of buckets formed between the inclined blades 20.

The stationary member 10 has a steam-inlet chamber 24, preferably at its upper part, which may be connected in any desirable manner with a suitable source of steam-supply and which discharges through a pair of diverging nozzles 25, leading to the opposite active side faces of the stationary member. Both nozzles incline in the same direction from the vertical axial plane of the turbine, which will be the direction of rotation of the movable members 13, and open to the outer series of blades 20 in elongated ports 26, as clearly shown in Fig. 2. The incline of the blades is such as to make them approximately at right angles to the direction of nozzle 25 in passing it, so as to receive the full impact of the steam-jet issuing therefrom. After receiving the impulse of the steam-jet from the nozzle 25, which causes the movable member to rotate, the buckets containing the steam come into register with the funnel-shaped mouth 27 of a transfer-nozzle 28 in the stationary member, which discharges through an elongated port 29 at an angle to the second series of blades 20, so as to discharge the steam thereon in a jet at right angles to the blades, as with nozzle 25. The buckets of the second or intermediate series of blades after receiving the partially-expanded steam from the nozzle 28 next come into register with the funnel-shaped mouth 30 of a transfer-nozzle 31 in the stationary member 10, which has an elongated port 32, opening to the innermost series of blades 20, similarly to nozzle 28. The buckets formed between the blades of the innermost series carry the expended steam from this port 32 to an outlet-port 33, which passes through the wall of the stationary member 10 into an exhaust-chamber 34 in the interior thereof, said exhaust-chamber having an exhaust-opening 35 connected with any suitable discharge. The buckets formed by the outer series of blades do not discharge all of their steam through the nozzle 28, but carry a portion of it beyond the funnel-shaped mouth 27 until they reach a similar funnel-shaped mouth 36 of an advance nozzle 37 in the stationary member 10, whose elongated outlet-port 38 opens to this same series of buckets farther along in the direction of rotation. There will be an advance of steam from the buckets as they pass this nozzle-mouth 36 to buckets in the same series ahead thereof, and this advance by reacting upon the blades of the buckets into which the steam is discharged will assist in the rotation of the movable member. The steam which

has been conducted to the advanced buckets in the outer series by means of the nozzles 37 is partially discharged into a funnel-shaped mouth 27' of a transfer-nozzle 28' in the stationary body portion 10, whose elongated outlet-port 29' discharges into the buckets of the intermediate series of blades, and thus further assists in the rotation of the movable member. This transfer-nozzle 28', leading from the outer series of buckets to the intermediate series of buckets, corresponds in every particular to the nozzle 28. A nozzle 31', corresponding to nozzle 31, is in the path of the buckets of the intermediate series to transfer such steam as may be received by its funnel-shaped mouth 30' through its elongated port 32' into the innermost series of buckets, from which it is discharged to the exhaust-chamber through ports 33', similar to port 33. The nozzles 37, 28', and 31' are repeated throughout the face of the stationary member 10 and have the same functions as those above described, so that by the time the buckets of all of the series of blades reach the nozzles first described they will be practically free from steam. It will be noted that all of the nozzles gradually increase in area of cross-section from their funnel-shaped mouths to their outlet-ports, which provides for the expansion of the steam and causes its rapid passage through the turbine, and the repeated arrangement of the nozzles assures the utilization of practically all of the available energy thereof.

The two sides of the turbine-engine being in duplicate and opposed to each other, there is practically no end thrust upon the parts, and the entire turbine is perfectly balanced, assuring its easy and efficient operation. Such steam as passes beyond the steam-tight joints around the movable members 13 will be retained by the outer casings 12 to assist by its back pressure in preventing a further escape, and when condensed the water of condensation may be drawn off through suitable drain-openings 39, which are normally closed by screw-plugs.

One of the features of advantage of this invention is the form of blade and its particular mounting by which it may be quickly and easily placed in position or removed when desired.

The invention is not confined to the particular details of construction and arrangement of parts here shown and described for the purpose of exemplification, for it is obvious that various changes may be made therein within the scope of the invention as defined by the claims.

What I claim as my invention is—

1. In a turbine-engine, a stationary member provided with active faces on opposite sides, a movable member formed in sections each having an active face co-operating with one of the active faces of the stationary

member, a sleeve on one section of the movable member projecting into an opening in the stationary member, and a boss on the other section of the movable member also 5 projecting in said opening and threaded in the sleeve to join the two sections of the movable member and cause the end thrust of each section to counteract the end thrust of the other section and thus balance the end pressures of the movable member.

2. In a turbine-engine, a stationary member and a movable member having active faces coöperating with each other, a pressure-nozzle discharging through one active face, a 15 series of blades supported on the other active face to receive pressure fluid from the nozzle, said blades comprising strips of metal angular in cross-section with one side longer than the other side to form a base engaging one 20 end in a groove in their support, and a securing-strip fastened to said support and having a shoulder to engage the opposite end of the base of the blades.

3. A turbine member having an active 25 face, a plurality of concentric series of blades in said active face comprising strips of sheet metal angular in cross-section with the portion in one plane longer than the portion in the other plane to form a base with end projections, said blades being embedded in a recess in the active face of the turbine member with one end projection of the outer and inner series of blades extending into grooves of the turbine member, and securing rings or 30 strips countersunk in the recess of the turbine member and having shoulders to engage the other end projections of the outer and inner series of blades and also the end projections of the intermediate series of blades, the 35 outer edges of the blades and the securing rings or strips being in the same plane with the active face of the turbine member.

4. In a turbine-engine, a stationary member and a movable member having coöperating active faces, concentric series of buckets on one active face, and pressure-nozzles on the other active face; said pressure-nozzles comprising a nozzle discharging into one series of buckets, another nozzle receiving the 45 pressure fluid from said series of buckets and transferring it to another series of buckets, and a third nozzle connecting the first-mentioned series of buckets with the buckets of the same series farther in advance.

5. In a turbine-engine, a stationary member and a movable member having coöperating active faces, concentric series of buckets on one active face, and pressure-nozzles on the other active face; said pressure-nozzles 55 comprising a nozzle discharging into one series of buckets, a set of nozzles receiving the pressure fluid from said series of buckets and

transferring it to another series of buckets, and another set of nozzles connecting the first-mentioned series of buckets with the 65 buckets of the same series farther in advance in the direction of rotation of the movable member.

6. In a turbine-engine, a stationary member having active faces on opposite sides, a 70 movable member having active faces to coöperate with the active faces of the stationary member, a number of concentric series of buckets formed in each active face of the movable member, there being an inlet-chamber and an exhaust-chamber for pressure fluid in the stationary member, a pair of diverging nozzles leading from the inlet-chamber to each of the active faces of the stationary member and discharging into the outer 75 series of buckets, and sets of transfer-nozzles in the active faces of the stationary member leading from each series of buckets to the inner series of buckets next thereto, the innermost series of buckets being adapted to discharge the pressure fluid through ports of the said exhaust-chamber.

In a turbine-engine, a stationary member having active faces on opposite sides, a 90 movable member having active faces to coöperate with the active faces of the stationary member, a number of concentric series of buckets formed in each active face of the movable member, there being an inlet-chamber and an exhaust-chamber in the stationary member for pressure fluid, a pair of diverging nozzles leading from the inlet-chamber to each of the active faces of the stationary member and discharging into the outer 95 series of buckets, sets of transfer-nozzles in the active faces of the stationary member leading from each series of buckets to the inner series of buckets next thereto, the innermost series of buckets being adapted to discharge the pressure-fluid through ports of the said exhaust-chamber, other sets of nozzles in the active faces of the stationary member adapted to receive the remainder of the pressure-fluid from the first-mentioned series of buckets after they pass by the transfer-nozzles and carry it to other buckets in the same series close to the next succeeding transfer-nozzle, pressure-tight connections between the movable member and the stationary member beyond the outer series of 100 blades, and pressure-tight casings connected to the stationary member and inclosing the movable member.

In testimony whereof I affix my signature in presence of two witnesses.

HENRY SCHEELE.
